PRESSURE VESSEL

Frederick E. Frey, Bartlesville, Okla., assignor to
 Phillips Petroleum Company, a corporation of
 Delaware

Application November 27, 1945, Serial No. 631,148

21 Claims. (Cl. 220—3)

1

This invention relates to vessels for containing fluid under pressure. In a more specific aspect, it relates to containers suitable for storing and transporting liquefied petroleum gas, compressed fuel gas, uncondensable gas, and other materials which must be held under superatmospheric pressure at room temperatures when the desired quantity thereof is in the container.

In the prior art, pressure vessels have been constructed as a cylindrical steel body which has been wound with steel wire in one or more layers. These prior art vessels take advantage of the high tensile strength of steel wire, and thereby make it possible to obtain greater resistance to internal pressure with a minimum weight of steel, considering both the steel of the cylindrical shell and the wire wound thereon.

I have found that certain organic fibers, preferably those composed of long chain molecules which molecules are preferably relatively highly oriented to give strength, exhibit very high tensile strength when compared with the tensile strength of steel wire if the weight of the fibers and the wire is taken into consideration. An outstanding example of these oriented fibers is "Nylon," which is a trade-name for a polyamide produced by condensing adipic acid and hexamethylenediamine. Other suitable fibers are "Rayon," which is a trade-name for a regenerated cellulose and "Saran," which is a trade-name for polyvinylidene chloride. The tensile strength of some of said fibers approaches that of steel wire, while the density is about one fifth that of steel. The present invention comprises means, apparatus, and structure whereby pressure vessels may be so constructed as to utilize the tensile strength of these organic fibers, of which the above mentioned fibers are merely representative, but are preferred.

While these organic fibers with their high tensile strength relative to their weight are capable of giving greater additional bursting strength to a vessel, with a resulting lower total weight than would be possible when using steel wire, the thermal coefficient of expansion or contraction of these fibers is greater than that of steel and other metals. The present invention overcomes this disadvantage of high thermal coefficient of expansion of the fibers.

One object of this invention is to provide a light-weight container for fluids under pressure.

Another object is to provide a container for fluids under pressure that will be light in weight as compared with all metal containers.

Another object is to provide a container for

2

fluids under pressure which is wound with organic fibers.

Another object is to utilize the strength of fibers having a higher coefficient of expansion than the pressure vessel around which they are wound as reinforcement.

Another object is to provide a container for fluids under pressure comprising a center shell having a relatively low coefficient of expansion and an outer shell capable of expansion commensurate with the expansion of a liquid between the two shells, the expansion of the outer shell under the influence of the expansion of the liquid being commensurate with the relatively high coefficient of expansion of organic fibers wound around the outer shell.

Another object is to provide a simple, and useful, container for fluids under pressure as shown and described, which will be economical in cost, and light in weight.

Numerous other objects and advantages will be apparent to those skilled in the art upon reading the accompanying specification, claims and drawings.

25 In the drawings—

Figure 1 is an elevational view of a container embodying the present invention with parts broken away and in cross section to show details of construction.

Figure 2 is a cross sectional view of a portion of Figure 1 taken along the line 2—2 looking in the direction indicated, with parts broken away to allow an enlarged view of said portion.

While an illustrative embodiment is shown in Figures 1 and 2 it should be understood that many other embodiments of the invention may be made within the scope of the present invention.

In Figure 1, there is shown an inner vessel 3 for containing a fluid under superatmospheric pressure. Vessel 3 may be provided with a suitable means for ingress and egress of pressure fluid 4, comprising a valve housing 5, cut-off valve 6 having the usual handle 7, and a connection 8 of any suitable type. If desired, any usual type of relief valve may be incorporated in house 5 with a passage communicating with fluid 4 for the relief of excessive pressure, but in order to simplify the disclosure such a relief valve is not shown.

Vessel 3 is preferably made of metal having relatively high bursting strength, such as steel, by any known method of making such vessels and valve housing 5 may be welded or brazed thereto. Welding material in holes 9, or any known at-

taching means between 3 and 5 may be employed such as screw threads. In fact, 5 could be integral with 3 but such construction is not preferred.

The outer shell or vessel 11 is formed around vessel 3 by any known method of metal fabrication leaving a space therebetween for a suitable liquid 12. Both vessels 3 and 11 may be made integral or in several parts suitably secured together by welding or pressed interlocking edges or other means old in the art, and vessel 11 is suitably secured to shell 3 by welding or other means at 13. In order to insert or remove liquid 12, a suitable filling valve 14 is preferably provided connected to shell 11 by suitable means 15. A simple plug could be used in place of valve 14, said plug being screw threaded or sealed to shell 11 at 15, but I prefer to employ a removable check valve 16 which will allow liquid 12 to enter vessel 11, but will not allow its egress. When it is desired to remove liquid 12, the inner parts valve 14 can be unscrewed or otherwise removed from house 15 as a tire valve core is removed from its housing.

While not necessary in some applications of the invention, it is desirable in larger vessels to provide spacing means such as semielliptical springs 17 to aid in centering and supporting vessel 3 inside vessel 11.

Vessel 11 is preferably made of thin metal and need not have very great strength. Vessel 11 is provided with a ribbed or corrugated construction, the corrugation being of the bellows type with straight sides (not shown) or preferably of the more or less sinuous corrugated construction shown in Figure 2 having depressed portions 18 and elevated portions 19. The rounded ends of vessel 11 will of course be made strong enough to resist the pressure of liquid 12.

Around the exterior of shell 11 is to be wound a thread or series of threads or cables 21 composed of organic fibers. It is preferable to employ overlapping, sliding segments 22 made of any suitable material for transmitting pressure from elevated portions 19 of shell 11 to fibers 21. Generally such segments 22 are preferably relatively thinner than shown in Figure 2 and may have their overlapping portions 23 tapered, if desired, in order to allow thread 21 to fit snugly against a substantially cylindrical outer surface presented by segments 22 instead of having the thread 21 merely touch higher points 19 of shell 11. Greater contact area between thread 21 and the surface of plates or segments 22 results in more equal distribution of force and there is less chance of failure of thread 21 because of concentrated stresses at any particular point.

Plates 22 may be made from any suitable organic or inorganic material but I prefer to use metal which may be secured by spots of solder or spot-welding to high points 19 at suitable intervals at points such as 24. When non-metallic substances are used glue or resins may be employed to fasten one or more points to shell 11, at least temporarily for purposes of assembly. However plates 22 may be free from shell 11 and held in assembled relation by a jig until thread 21 is cemented in place and then will be held in place by the cement on thread 21.

Certain embodiments of my invention may eliminate plates 22, winding thread 21 directly on shell 11 with favorable results but such embodiments are not preferred.

Thread 21 may be wound on in one or more layers and may be composed of a single thread or cable of threads or a plurality of threads 75

wound in series. I prefer to use a single strand for 21 and I prefer when using strands, threads or cables, to employ them with fibers oriented with the fiber length in the direction of length 5 of the strand, thread or cable, that is longitudinally disposed in the thread or stand, in order to obtain the maximum tensile strength from the fibers. For fibers in 21 I prefer "Nylon," "Rayon" or "Saran" but those skilled in the art 10 may easily select other suitable organic fibers which may be employed without departing from the scope of the present invention. "Nylon" has a high degree of orientation. While direct helical winding is preferred, a woven or knitted, 15 felted or other fabric jacket may be employed in some instances in place of thread 21.

While the ends of thread 21 may be secured by any suitable securing means to segments 22 or shell 11, I prefer to overlap one or more turns 20 of thread 21 and then paint the entire winding with any suitable glue, cement or resin such as a good spar varnish or a resin polymer such as "Duco" or the complete vessel may be dipped in gummed rubber which may be allowed to dry or 25 which may be vulcanized. It should be easy for those skilled in the art to select suitable glue, cement or resins compatible with the particular thread 21 employed, be it "Nylon," "Rayon," "Saran" or other organic fibers, and by rubber 30 I intend to include synthetic rubber. Preferably the coating material chosen should have elasticity compatible with the usual expansion of thread 21 under normal operating conditions.

Liquid 12 may be any suitable liquid having a 35 coefficient of expansion commensurate with the coefficient of expansion of the organic fiber or fibers selected for use as thread 21. I have found that hydrocarbon liquids, such as ether, butane, kerosene and other naphthas are generally 40 preferable as liquid 12. Those skilled in the art can easily select a suitable fluid for 12 for the particular organic fiber used in 21 and still remain within the scope of the present invention.

Operation
45 Vessel 3 and its valve housing 5 is assembled and outer shell 11 is assembled around it. If plates 22 are employed, they are then at least temporarily positioned, or more or less secured to and around shell 11; but if plates 22 are 50 not employed thread 21 is then wound directly on shell 11. The winding of thread 21 on shell 11, or in plates 22, may be made before or after liquid 12 is inserted between shells 3 and 11, but preferably before complete insertion. After 55 thread 21 is wound on and secured to the vessel as described it may or may not be painted with a suitable coating material such as the glues, resins, cements and other materials described above.

60 Liquid 12 is filled in the space between 3 and 11 preferably without any air bubbles or other gaseous inclusion in order to obtain the full effect of its coefficient of expansion.

The vessel is now filled with fluid under pressure through connection 8 and valve 6 is closed.

Upon increase in temperature, thread 21 will expand to a greater degree than shell 3 but liquid 12 being a liquid of relatively high thermal coefficient of expansion such as ether, butane, kerosene, naphtha or the like, will expand at a rate commensurate with the expansion of thread 21 causing corrugations 18 and 19 of shell 11 to tend to straighten out and maintain pressure on threads 21.

Thus, the pressure exerted by the compressed

5

fluid 4 is transmitted through shell 3 and liquid 12 to the outer shell 11, where it is off-set or neutralized by the tension of the fibers in the winding 21. The liquid in the annular space and also the thickness of this annulus is so selected that the expansion or contraction with the change in temperature during normal transport and storage of the liquid 12 is such that a state of substantially constant tension is maintained, or at least the tension is maintained in a safe range in the layer or layers of organic fibers windings 21. The shell 11 which contains the liquid annulus should be sufficiently expandable to allow it to expand and contract with change in temperature and thus maintain the hydrostatic pressure of the liquid 12 at a safe value.

Besides securing thread 21, the coating of glue or other materials suggested above has the additional function of preventing access of moisture or oxygen to thread 21 so that the organic fiber 21 will be preferably protected with a substantially air-tight, moisture-resistant coating.

Numerous changes may be made in the specific embodiments of the invention described without departing from the spirit and substance of the invention, the scope of which is commensurate with the following claims.

Having described my invention I claim:

1. A pressure vessel comprising in combination an inner shell adapted to receive fluids under superatmospheric pressure, an outer corrugated expandible shell, an elastic synthetic organic fiber reinforcement for said outer shell having a coefficient of expansion substantially greater than the coefficient of expansion of said inner shell, and a liquid filling the space between said shells, said liquid having a coefficient of expansion substantially commensurate with the coefficient of expansion of said organic fiber reinforcement, whereby upon expansion and contraction due to normal temperature changes the tension on said fiber reinforcement is maintained in a safe range.

2. The combination of claim 1 in which the elastic synthetic organic fiber reinforcement is a polyamide.

3. The combination of claim 1 in which the elastic synthetic organic fiber reinforcement is a regenerated cellulose.

4. The combination of claim 1 in which the elastic synthetic organic fiber reinforcement is a polyvinylidene chloride.

5. The combination of claim 1 in which the liquid is a hydrocarbon.

6. A pressure vessel comprising in combination an inner shell adapted to receive fluids under superatmospheric pressure, an outer corrugated expandible shell, overlapping plates disposed around said outer shell and secured thereto, a liquid filling the space between said shells, a helical winding of an elastic thread of a synthetic organic fiber around said plates, means securing the end of said thread, and a coating of a suitable coating material covering said thread whereby said organic fiber is substantially protected from air and moisture.

7. A pressure vessel comprising in combination an inner shell adapted to receive fluids under superatmospheric pressure, an outer corrugated expandible shell, overlapping plates disposed around said outer shell and secured thereto, a liquid filling the space between said shells, a plurality of layers of helical winding of a continuous single strand of thread of a synthetic organic fiber around said plates, means securing the end of said thread, and a coating of a suitable coating

6

material covering said thread whereby said organic fiber is substantially protected from air and moisture.

8. A pressure vessel comprising in combination an inner shell adapted to receive fluids under superatmospheric pressure, an outer corrugated expandible shell, overlapping plates disposed around said outer shell, a liquid filling the space between said shells, a plurality of layers of helical winding of thread of a synthetic organic fiber around said plates, means securing the end of said thread, and a coating of a suitable coating material covering said thread whereby said organic fiber is substantially protected from air and moisture.

15 9. A pressure vessel comprising in combination an inner shell adapted to receive fluids under superatmospheric pressure, an outer corrugated expandible shell, overlapping plates disposed around said outer shell and secured thereto, a liquid filling the space between said shells, a helical winding of synthetic organic fiber around said plates, and means securing the end of said thread.

20 10. A pressure vessel comprising in combination an inner shell adapted to receive fluids under superatmospheric pressure, an outer corrugated expandible shell, overlapping plates disposed around said outer shell and secured thereto, a liquid filling the space between said shells, a winding of a thread of synthetic organic fiber around said plates, means securing the end of said thread, and a coating of a suitable coating material covering said thread whereby said organic fiber is substantially protected from air and moisture.

25 11. A pressure vessel comprising in combination an inner shell adapted to receive fluids under superatmospheric pressure, an outer corrugated expandible shell, overlapping plates disposed around said outer shell, a liquid filling the space between said shells, a winding of synthetic organic fiber around said plates, means securing the ends of said fiber comprising a coating of a suitable coating material covering said ends of said fiber and said fiber whereby said organic fiber as 30 well as the ends is substantially protected from air and moisture.

35 12. A pressure vessel comprising in combination an inner shell adapted to receive fluids under superatmospheric pressure, an outer corrugated expandible shell, overlapping plates disposed around said outer shell, a liquid filling the space between said shells, a winding of a thread of synthetic organic fiber around said plates which fiber has a coefficient of expansion substantially commensurate with the coefficient of expansion of 40 said liquid, and means securing the end of said thread.

45 13. The combination of claim 12 in which the organic fiber reinforcement is a polyamide.

50 14. The combination of claim 12 in which the organic fiber reinforcement is a regenerated cellulose.

55 15. The combination of claim 12 in which the organic fiber reinforcement is a polyvinylidene chloride.

60 16. The combination of claim 12 in which the liquid is a hydrocarbon.

65 17. The invention of claim 11 in which the coating material is a spar varnish.

70 18. The invention of claim 11 in which the coating material is a resin polymer.

75 19. The invention of claim 11 in which the coating material is a rubber.

20. A pressure vessel comprising in combination an inner shell adapted to receive fluids un-

der superatmospheric pressure, an outer corrugated shell, spacing means between said inner and outer shells, overlapping plates disposed around said outer shell, a plurality of layers of helical winding of elastic synthetic organic fiber around said plates, means securing the end of said fiber, a coating of a suitable coating material covering said fiber whereby said fiber is substantially protected from air and moisture, and a liquid filling the space between the space between said inner and outer shells.

21. A pressure vessel comprising in combination an inner shell adapted to receive fluids under superatmospheric pressure, an outer corrugated shell, spacing means between said inner and outer shells comprising semielliptical springs, overlapping plates disposed around said outer shell, a plurality of layers of helical winding of elastic

synthetic organic fiber around said plates, means securing the end of said fiber, a coating of a suitable coating material covering said fiber whereby said fiber is substantially protected from air and moisture, and a liquid filling the space between said inner and outer shells.
